DEVICE FOR ANNEALING WORKPIECES

William E. Engelhard, Apalachin, N.Y. (% Temperature Processing Co. Inc., 228 River Road, North Arlington, N.J.)

Filed Oct. 29, 1962, Ser. No. 233,586
6 Claims. (Cl. 266—5)

This invention relates to the art of annealing workpieces in the opening of a heating member such as the opening of a high temperature furnace, such as shown, for example, at 28 in my Patent 2,744,745 issued May 8, 1956. The present invention constitutes an important improvement over the said patent, as set forth below, and illustrated in the drawings and recited in the claims. In the annealing of workpieces in such high temperature furnaces, the workpieces are flushed with a gas such as hydrogen or helium. As metals become increasingly porous at higher temperatures, a certain amount of gas diffusion therethrough occurs; it is important to exclude ambient atmosphere from workpieces being annealed and prevent back flow or diffusion of moisture and air, or other unwanted vapors or gases. One method of attempting to do this would be to pump the purified gases over the workpieces in such volume and high rate so as to flood the workpieces with rapidly wasted gases.

Another method is to use high vacuum to minimize the expense of the workpieces to unwanted gases or vapors at high temperatures. This latter increases the difficulties of excluding unwanted gases and of obtaining uniform heating or the high speed coating frequently necessary at the end of the cooling cycle.

The present invention provides a means of accomplishing uniform heating in an envelope of pure gas at or near normal atmospheric pressure, provides a means of using protective gases in minimal amounts both for reasons of economy and temperature uniformity, provides a means of final gas purification immediately before it envelopes the work, provides a means of baffling the outward flow of said protective gas to flush away and push-back from the workpieces any unwanted gases and vapors, provides a means whereby said workpieces may be quenched directly in liquid quench mediums with no intermediate exposure to the air.

The invention is useful in connection with furnaces opening in any direction.

The device of the present invention provides a predetermined path for the flow of gases from the innermost portion of the device through an external seal such as to resist and prevent return flow, the gases being directed first over the workpieces and then through a tortuous path excluding return flow of moisture, oxygen and other impurities. A further feature of the invention is to provide a "getter" disposed internally of the device and through which the gas must flow prior to bathing the workpieces, purifying the gas so applied and assuring clean bright brazing, hardening, and annealing of the work. It is further possible, pursuant to the present invention, to transfer the work and holder from the furnace to a quenching bath without interruption of the work-sealing procedure.

In the drawings:

FIG. 1 is a vertical sectional view, partly fragmentary, of a method and apparatus embodying the invention, FIGS. 2 and 3 are similar views of other forms thereof.

2

In the drawings, an annealing apparatus 10 embodying the invention is shown disposed in the opening 11 of a heating member such as a furnace 12 which may have heating elements 13 or the like to attain desired temperatures. The opening 11 of the furnace may be substantially closed by a cover plate 15 which may consist of two or more parts and which may have an opening 16 through which the vent sleeve 17 of the device 10 passes. A gas supply pipe 18 is connected at one end to one or more sources 40, 41 of supply of gas such as hydrogen or helium under pressure, for use with workpieces of stainless steel, argon or titanium etc. The other end of the gas pipe 18 may be secured as at 19 by welding or the like to the top plate 20 of the inner casing 21, telescopically enclosing the parts 14. The lower end 22 of casing 21 is disposed in spaced relation to the bottom of the tubular baffle housing 23, being U-shaped in cross section, casing 21 being welded or otherwise secured as at 24 to the top plate 20. The work parts 14 as above noted are positioned on the baffle housing 23 and within the inner casing 21. A holder 39 is positioned on the uppermost of the parts 14 to be treated and has disposed therein a quantity or layer of metallic or mineral wool 25 such as silicon carbide, stainless steel wool, asbestos wool, glass wool, which as presently available, are heat resistant in the order given. The stainless steel wool is a "getter", the other materials mentioned are substantially inert. Said holder 39 may be of wire mesh or other construction so as to permit the free flow of gases therethrough and onto the workpieces from pipe 18 which opens as at 42 interiorly of the inner casing 21. The wool 25 may be any suitable gas purifier, such as stainless steel wool, or silicon carbide wool with a sprinkling or layer of titanium or other grains 26 to serve as a "getter" for purifying the gas passing through the pipe 18 and prior to the gas flushing the work 14 in casing 21. Thus, in operation, the gases pumped through the pipe 18 are freed of moisture and oxygen and wash the parts 14 to be sealed against the ambient atmosphere, flowing, as shown by the arrow 27, from the lower end 22 of the inner casing 21 upwardly between said inner casing 21 and the outer casing wall 29 of the inner housing. The plate 20 preferably also has downwardly extending therefrom the outer casing wall 29, thereby secured to the pipe 18 and held thereby in spaced relation to the bottom of outer casing 28, so that the gases flowing upwardly as indicated by the arrow 27 intermediate the inner casing 21 and the housing 23 with then flow downwardly as indicated by the arrow 27a between the baffle housing 23 and the outer wall 29 of the inner housing and thence again upwardly as indicated by the arrow 30, intermediate the outer housing wall 28 and outer wall 29 of the inner housing. The gas then flows through the sealing ring 31 securing to the outer housing as at 32 and disposed in relation to the outer housing 28 and cover plate 47 (the latter is welded to sleeve 17 as at 48). The sealing ring 31 may contain a suitable sealing agent such as silicon carbide sand which ambient moisture and impurities would have to initially penetrate to inner casing 21. Contamination by entry of moisture laden air and impurities is minimized by continuous ring 33 of silicon carbide wool or sand or other material which provides a restricted passageway which will not permit the reverse flow of contaminating air or impurities, while enabling

gas to flow as indicated by arrows 43 and 36 between the pipe 18 and sleeve 17 and thence out of the discharge pipe 37 for burning or discharge into the atmosphere directly or through a bubbling tank 44 for back pressure and indication of flow. The sleeve 17 may be provided with a stuffing box collar 38 to permit relative smooth sliding movement between the sleeve 17 and the pipe 18.

Pipe 18 and plate 20 may be coupled to elevating and lowering mechanisms by conventional means as through brackets 45, 46 for lowering said sleeve and pipe in unison or selectively into the opening 11 and then the cover plate 15 may be used to substantially close said opening around the sleeve 17. On completion of the annealing procedure the sleeve 17 and pipe 18 and associated parts may be elevated in unison or separately out of the opening 11 and into a quenching medium. Such movement of the parts may be achieved without interrupting the continuous flow of gas in accordance with the procedure above set forth and disclosed herein.

The stuffing box collar 38, as above noted, enables relative smooth sliding movement between the sleeve 17 and the pipe 18; the sleeve 17 and plate 47, secured thereto as at 48, may simply rest on and press against the ring 33, in which case the brackets 45, 46 may be engaged and the parts elevated and then positioned in a liquid quenching medium; the latter will tend to cover the parts 28 and associated parts, which are heavier and thus settle first in the quenching tank. The plate 47 and sleeve 17 are lighter and thus on movement 30 into the liquid in the quenching tank stay above the outer housing 28. The top plate 20 may be elevated to thereby carry the plate 47 therewith by grasping the bracket 45 and moving the parts upwardly. The work 14 and associated parts, remaining within the quenching medium, will cool uniformly and while completely sealed from the atmosphere by the immersing liquid. Gases are passed through pipe 18 while the parts are removed from the furnace and deposited into the quenching tank.

The outer housing 28 and associated parts may, instead of being deposited into a liquid quenching medium, be simply lifted out of the furnace 12 and left suspended in ambient air, preferably while gas is continuously passed through pipe 18 to immerse the parts in the gas. Air may be blown against the outer housing 28 until the latter is brought down to substantially room temperature. Another procedure which may be used is to lift the assembly of outer housing 28 and associated parts from the furnace by engaging and elevating brackets 45, 46 and then positioning the parts over the quenching tank; then, by holding bracket 45 while permitting brackets 46 to be lowered, the parts 28, 23, 21 will be immersed in the quenching medium. Other quenching procedures may be resorted to in carrying out the invention, the above being exemplary.

In FIG. 2 the cover plate 47 does not have a down-turned marginal edge extending into sealing ring 33 and may comprise a layer 49 of silicon carbide wool, for example—which is very satisfactory for the purpose, being a good insulator and standing up well under diverse temperatures. In the FIG. 2 form of the invention the gases may pass out of the outer housing 28 as at 50, where they will (due to the furnace heat) burn or they may escape to the atmosphere. In the FIG. 2 construction the cover plate 47' is proportioned to fit within the upper edge of the outer housing, leaving a very slight space for escape of gases; this form of invention is adapted for use where the atmosphere can tolerate the particular type of gas being passed through pipe 18. The parts of the FIG. 2 construction corresponding with those of FIG. 1 and described in connection with the latter figure, are correspondingly numbered.

The FIG. 3 form is generally similar to the FIG. 2 form in the parts that are correspondingly numbered, but in FIG. 3 the work may be positioned on the bottom of the U-shaped housing 23 or on the bottom of an innermost baffle housing 52, positioned in turn on the bottom of the housing 23, and the gas supply pipe 18 is extended so as to terminate on or in the gas purifying device 54, the work in turn being positioned on the device 54 instead of the reverse arrangement shown in FIGS. 1 and 2. The gas passes through the pipe 18, through purifier 54 and thence upwardly as at 55, over the top of the innermost housing 52 and downwardly between housing 52 and inner casing 21 and thence ultimately out as at 50. The parts in FIG. 3 corresponding to those of FIGS. 1 and 2 are correspondingly numbered. The cover plate 47' and the sleeve 17 press down on the sealing ring 49 to compress the latter between plate 47' and top plate 20 and essentially seal the latter and the outer casing 28.

Having thus described my invention, what I claim as new and desire to secure by Letters Patent is:

1. A device for annealing workpieces in a furnace under a selected gaseous medium without exposing them to atmosphere, comprising:

- (a) a continuous wall outer housing of uniform cross-section disposed in said furnace and which has one closed end and one open end;
  - (b) a cover plate which is fitted over said open end of said outer housing and has a periphery slightly spaced from the wall of said outer housing;
  - (c) a sealing medium interposed between the outer housing adjacent said one open end and the periphery of said cover plate;
  - (d) a vent sleeve rigidly connected to said cover plate and which extends up and out of said furnace;
  - (e) an inner housing within said outer housing which has an inner casing and an outer casing, both of similar cross-section, said casings being continuous closed walls concentrically disposed in spaced relation to each other;
  - (f) both said inner casing and said outer casing being open at the same one end and the other ends thereof being closed by an inner housing top plate which is integral therewith and is slightly spaced from said cover plate;
  - (g) the outer casing of said inner housing being spaced a small distance from said outer housing and the inner casing of said inner housing enclosing a workpiece positioned therein;
  - (h) a gas supply pipe in said vent sleeve which extends down into said inner housing through said inner housing top plate and to which it is rigidly connected;
  - (i) said inner housing walls at their open end being spaced from said closed end of said outer housing;
  - (j) an intermediate closed wall baffle housing disposed between said concentric spaced walls of said inner housing in spaced relation thereto and having one end in engagement with said closed end of said outer housing wall and having its other end open and spaced from said top plate, all of said walls thereby forming a tortuous path for flow of gas from the interior to the exterior of said inner housing and;
  - (k) a purifying filter integrally connected with said inner wall of said inner housing and disposed between said gas supply pipe and said workpiece so that all gas must pass from said gas supply pipe and through said filter before reaching said workpiece.
2. A device for annealing workpieces as set forth in claim 1, wherein:
- (a) lift engaging means is provided on said outer housing for lifting said device from said furnace.
  - 3. A device for annealing workpieces as set forth in claim 2, wherein:

(a) lift engaging means is provided on said gas supplying means for lifting only said gas means, said inner housing, and said top plate from said furnace.

4. In a device as set forth in claim 1, said purifying filter comprising silicon carbide wool.

5. In a device as set forth in claim 1, said purifying filter comprising steel wool and metallic particles.

6. In a device as set forth in claim 5, said particles comprising grains selected from the following group or a combination thereof: titanium, silicon, aluminum.
